STRAND HANDLING APPARATUS

Leo L. Weaver, Cranford, N. J., assignor to Western Electric Company, Incorporated, New York, N. Y., a corporation of New York

Application October 10, 1940, Serial No. 360,580

5 Claims. (Cl. 57—15)

This invention relates to strand handling apparatus, and more particularly to high speed apparatus for serving a plurality of cover strands upon a core strand in one operation.

In various manufacturing arts, and especially in the art of making insulated electrical conductors, it is necessary to wind one or more strand in the form of a substantially complete sheath or cover around another strand. The central or axial strand is ordinarily called the core strand, or simply the core. This is usually not twisted or distorted in the operation. The strand or strands wound upon the core are called cover strands. In the case of insulated electrical conductors, the core is a metal wire or a plurality of intertwined or interbraided wires; and the cover strands may be of any desired material adapted to the particular purpose in view, e. g. threads, ends or yarns, or the like, of silk, cotton, wool, artificial silk, spun glass, or other material. To wind or serve such cover strands upon a core, there must be relative longitudinal motion either of a supply of cover strand along the core or of the core longitudinally past the supply; and, at the same time, there must be rotary motion either of the supply about the core or of the core about the supply or of the core about its own axis beside the supply.

An object of the present invention is to provide an apparatus for simultaneously serving cover strands upon a torsionally substantially rigid core at a plurality of points thereon, to form a plurality of coverings upon the core in one operation.

With the above and other objects in view, the invention may be embodied in an apparatus comprising means to individually impose axial rotation upon each of a plurality of separate portions only of a longitudinally advancing torsionally substantially rigid core and to annul such rotation at the end of each such portion, together with means associated with each axially rotating portion of the core to supply cover strand thereto.

Other objects and features of the invention will appear from the following detailed description of an apparatus constructed in accordance with the invention taken in connection with the accompanying drawings in which the same reference numerals are applied to identical parts in the several figures and in which

Fig. 1 is a diagrammatic view in elevation of an apparatus constructed in accordance with the invention;

Fig. 2 is a partial view on the line 2—2 of Fig. 1;

Fig. 3 is a partial view on the line 3—3 of Fig. 1;

Fig. 4 is a showing similar to Fig. 3 of a modified arrangement;

Fig. 5 is partial view on the line 5—5 of Fig. 1; and

Fig. 6 is a side view of a piece of one product of the machine much enlarged.

In the machine disclosed, a framework 30 has mounted therein a duplex fier generally indicated by the numeral 31 and having exit and entrance arms 32 and 33 respectively. The strand exit ends of both arms of the fier are supported in and drive a stub shaft 34 journaled in the frame in any approved manner. The strand entrance ends of the two arms of the fier are supported in and driven by a stub shaft 35 also journaled in the frame in axial alignment with the shaft 34. The arm 33 at its lower end opens in the axis of the shaft 35 at the bottom end thereof and at its upper end the arm 33 opens out axially from the bottom end of the shaft 34. Similarly the lower and upper ends of the arm 32 open out respectively from the centers of the upper ends of shafts 35 and 34.

A supply support 36 is journaled on the upper end of the shaft 35 and carries means including strand guides 55 to support a plurality of supply cops 37 with freedom to rotate on their own axes.

Shaft 35 is provided at its lower extremity with a spur gear 38. Above its bearing the frame is formed with a spur gear 39. Gear 39 meshes with a planetary gear 40 mounted on the lower end of a shaft 41 journaled in a bracket on the shaft 35 and having at its upper end a second planetary gear 42. Gear 42 in turn meshes with a spur gear 43 carried by the supply support 36. Gear 38 meshes with and is driven by a gear 44 mounted on a shaft 45 journaled in the frame 30. Shaft 45 in turn is driven from a power shaft 46 through bevel gears 47 and 48. Shaft 46 is driven from any convenient power source not shown, and drives a take-up reel 49 through an appropriate belt 50 and pulleys 51 and 52.

A core supply 53 is mounted below the bottom ends of the shaft 35 and fier arm 33. A capstan 54 is provided to assist the take-up reel in pulling the strand through the apparatus.

The core 56 is a wire or other strand analogous to a wire in being torsionally substantially rigid so that it does not accept any twist or torsional deformation to any substantial extent in its progress through the apparatus.

The space within the fier 31 is divided into three sub-spaces by transverse crossbars or braces 28 and 29. The supply frame or support 36 is within the lower space below the crossbar

29. A second duplex flier, generally indicated at 21 and having exit and entrance arms 22 and 23 respectively, is positioned within the middle space of the flier 31, between the crossbars 28 and 29; and a second cover strand supply support 136 is positioned within the flier 21. A third cover strand supply support 236 is positioned within the upper space of the flier 31 above the crossbar 28.

The flier 21 terminates below in a hollow shaft 135 journalled in the crossbar 29, extending through the crossbar and journalled also in the top of the supply frame 36 to steady the latter axially. A spur gear 58 is secured on the top of the frame 36 and surrounds the shaft 135 which is rotatable within it. A planetary gear 59 meshes with the gear 58 and is rigidly secured on the lower end of a shaft 60 rotatably mounted in the crossbar 29. On the upper end of the shaft 60 is rigidly but removably mounted in any suitable fashion, a gear 61, which meshes with a gear 62 rotatable on a removable support 63 carried on the crossbar 29. The gear 62 meshes in turn with a spur gear 64 rigidly secured to the under side of the flier 21 and split as shown in Fig. 3 to be removable.

The cover strand support 136 is journalled on and supported below by a short upward extension of the shaft 135 of the flier 21. The upper part of the support 136 is journalled similarly on a downward extension of the shaft 134 of the flier 21. A gear 143 surrounds the shaft 134 rotatably thereon and is secured to the support 136 on the upper side thereof. This gear 143 is operatively connected through planetary gears 142 and 140 on a shaft 141 carried by the crossbar 28, to a gear 139 rigid on the bottom end of an extension 65 of the cover strand supply support 236, journalled in the crossbar 28. The extension 65 is hollow to receive and support rotatably therein the shaft 134 of the flier 21.

The top of the support 236 is similarly operatively connected through gears 239, 240, shaft 241, and gears 242 and 243 to the top of the fixed frame 30.

The shaft 35 and thereby the flier 31 are driven in rotation, say counterclockwise looking down from the top of Fig. 1 in the direction of the arrows 2-2 and 3-3. The gears 39 and 43 are of identical size as are also the gears 40 and 42. The gear 39 being stationary because rigid on the fixed frame 30, the gear 43 must remain stationary and hold the frame 36 stationary while the flier 31 revolves about it.

The gear 58 is stationary and therefore drives the planetaries 59 and 61, which are unequal in size and hence drive the gears 62 and 64, the latter at a speed and in a direction relative to the stationary gear 58 which will depend upon the relative sizes of the several gears from 58 to 64 inclusive. These are intended here to be such that the gear 64 and the flier 21 secured thereto will rotate in the same direction as the flier 31 but at twice the speed of the latter.

Looking now at the top of Fig. 1, the gear 239 is stationary, being secured to the frame 30, and hence the gear 243 and the support 236 secured thereto are stationary, the gear train 239, 240, 242, 243 being identical in kind to the train 39, 40, 42, 43. Likewise the gear 139 is stationary, being secured to a part of the stationary support 236, and thus maintains the gear 143 and therewith the support 136 stationary.

When the apparatus as thus described is in operation, assuming that the core strand 56 is

torsionally substantially rigid, the core 56 is drawn from the supply reel 53 by the capstan 54 and take-up reel 49. From the supply reel 53 the core passes up into the bottom of and through the entrance arm 33 of the flier 31. Emerging downwardly from the top of this flier arm, the strand is rotating on its own axis in the same direction as the flier, i. e. counterclockwise as seen from above, and at twice the speed of the flier. As it passes on down into the upturned end of the entrance arm 23 of the inner flier 21, the cover strands 157, drawn from the cops 137 on the stationary support 236, are wound around the rotating core by the rotation of the latter.

As the now once wrapped core passes down into the entrance of the flier 21, both the core and the flier 21 are rotating in the same direction and at the same speed. There is, therefore, no rotation of the flier 21 with respect to the core entering into it. Therefore, the entire flier has no effect upon the rotation of the core. On emerging from the arm 23, the core is stationary with respect to the flier 21 but is rotating with respect to the stationary packages or cops 137 of cover strand at twice the speed of the flier 31, i. e. at the speed of the flier 21 with respect to the cops. The cover strands 157 are wound on the core as a second serving of the same pitch as the first, but of opposite hand because the core, rotating in the same direction as before, is passing the winding point in the opposite longitudinal direction.

The then doubly wrapped core emerges downwardly from the flier 21 at the bottom or exit end of the arm 22, still rotationally stationary with respect to this flier and therefore rotating with respect to the stationary supply cops 37 in the same direction as and at twice the speed of the flier 31. The cover strands 57 are then wound as a third serving over the second and of the same pitch and hand as the first serving.

Finally the trebly served core enters the arm 32 at the bottom and emerges at its top without rotation and is taken up on the reel 49. The product thus made is a trebly served core, of which the three servings are of one pitch but of alternating left, right and left hand.

This mode of operation, in which the inner flier turns in the same direction as the outer flier but at twice the speed of the latter and therefore has no effect upon the axial rotation of the core passing through it but serves only to reverse the longitudinal direction of passage of the core past a stationary winding point is a unique and special mode of operation of the apparatus, by virtue of the fact that the flier 21 does not affect the rotation of the core.

Assume now that the gear train 58 to 64 is such that the flier 21 is driven at three times the speed of the flier 31 but still in the same direction. The flier 21 is then running ahead of the once served core entering it by three to two. The once served core, therefore, comes to the second serving point with two additional rotations for every two it had upon entering the flier 21, and is rotating now at four times the speed of the flier 31 and still in the same sense with respect to the stationary cops 137. The strands 157 are wrapped on the core by its rotation in same sense as before, i. e. right handedly, but at half the pitch, so that only half as many cover strands 157 as in the first case will give the same coverage.

Now, if the gear 62 be omitted as shown in Fig. 4, and the train of gears from 58 to 64 be suitably proportioned, the flier 21 may be driven in the opposite direction of rotation to that of the flier 31. Then the rotation of the once served core at the second or middle winding point may be reversed in direction, thus causing the middle wrapping or serving to be of the same hand as the first and third servings and of any pitch desired within reasonable limits imposed by the gear dimensions. The first and third servings are, of course, identically alike in pitch and hand in any case.

For the sake of simplicity of drawing and clarity of description, the planetaries 40 and 42 are shown as unique; but in practice it might be preferable to balance these by identical parts engaging the gears 39 and 43 respectively at diametrically opposite points to provide centrifugal balance. Similarly the gearings 57-62, 140-142, and 240-242 might be duplicated at the opposite sides of their respective sun gears for the same reason.

The flier 31 is shown as divided into three quasi compartments, of which the middle one contains the flier 21. As thus arranged, three coverings are served simultaneously on a core in one operation. By increasing the length of the flier 31 and the number of crossbars 28 and 29, more than one internal flier 21 and cover strand supply 136 may be installed within the flier 31; and thus the number of coverings served on the core in one passage through the machine may be increased.

If either the support 36 or the support 236 with their strand supplies be omitted from the machine of Fig. 1, or if merely the supplies on them be omitted, the core will be wound with two coverings in one passage through the medium; and these coverings will be of like or opposite hand and of like or unlike pitch according to the relative speeds and directions of the two fliers.

The flier 31 acts to impose upon the torsionally rigid core the rotation of the core about its axis which effects the winding upon the core of the cover strands 57 and 257 at the bottom and top winding points respectively. In the first mode of operation above described with the flier 21 turning in the same direction as the flier 31 but at twice the speed of the latter, the flier 21 acts to preserve the rotation of the core unchanged but to reverse the longitudinal direction of the core past the intermediate winding point and thus to reverse the hand of the lay of the cover threads 157 on the core. If the speed or direction of rotation of the flier 21 is any other than twice the speed and in the same sense as the rotation of the flier 31, the flier 21 will impose on the core at the intermediate winding point an additional rotation which will be with or against that caused by the flier 31 according as the flier 21 runs ahead of the flier 31 or behind or against it.

The particular embodiment disclosed is illustrative and may be modified and departed from in various ways without departing from the spirit and scope of the invention as pointed out in and limited only by the appended claims.

What is claimed is:

1. Strand handling apparatus for serving cover strands at a plurality of points simultaneously upon a longitudinally advancing torsionally rigid core strand, which apparatus comprises a primary rotatable duplex flier having an entrance arm and an exit arm to receive and guide the

core strand, a plurality of stationary supports for cover strand supplies within the flier at respective winding points in sequence between the exit end of the entrance arm and the entrance 5 end of the exit arm, and a secondary rotatable duplex flier within the primary flier having an entrance arm and an exit arm to receive and guide the core strand, one of the cover strand supply supports and the winding point associated therewith being within the secondary flier between the exit end of the entrance arm thereof and the entrance end of the exit arm thereof.

2. Strand handling apparatus for serving cover strands at a plurality of points simultaneously upon a longitudinally advancing torsionally rigid core strand, which apparatus comprises a primary rotatable duplex flier having an entrance arm and an exit arm to receive and guide the core strand, a plurality of stationary supports for cover strand supplies within the flier at respective winding points in sequence between the exit end of the entrance arm and the entrance end of the exit arm, a secondary rotatable duplex flier within the primary flier having an entrance arm and an exit arm to receive and guide the core strand, and means to rotate the two fliers at constant speeds, one of the cover strand supply supports and the winding point associated therewith being within the secondary flier between the exit end of the entrance arm thereof and the entrance end of the exit arm thereof.

3. Strand handling apparatus for serving cover strands at a plurality of points simultaneously upon a longitudinally advancing torsionally rigid core strand, which apparatus comprises a primary rotatable duplex flier having an entrance arm and an exit arm to receive and guide the core strand, a plurality of stationary supports for cover strand supplies within the flier at respective winding points in sequence between the exit end of the entrance arm and the entrance end of the exit arm, a secondary rotatable duplex flier within the primary flier having an entrance arm and an exit arm to receive and guide the core strand, and means to rotate the two fliers at constant speeds, one of the cover strand supply supports and the winding point associated therewith being within the secondary flier between the exit end of the entrance arm thereof and the entrance end of the exit arm thereof.

4. Strand handling apparatus for serving cover strands at a plurality of points simultaneously upon a longitudinally advancing torsionally rigid core strand, which apparatus comprises means to impose rotation upon a portion only of the advancing core strand and to modify the motion of a part only of the rotating portion, in combination with means to supply cover strands to the core strand at a point on the modifiedly moving part of the core strand and at another point on the unmodifiedly moving portion of the core strand to be served thereon by the rotation thereof.

5. Strand handling apparatus for serving cover strands at a plurality of points simultaneously upon a longitudinally advancing torsionally rigid core strand, which apparatus comprises means to impose rotation upon a portion only of the advancing core strand and to modify the motion of a part only of the rotating portion, the said means including a primary rotatable duplex flier

having an entrance arm and an exit arm, and a secondary rotatable duplex flier arm positioned within and coaxially with the primary flier to receive the core strand from the entrance arm of the primary flier and deliver it to the exit arm thereof, in combination with means to supply

cover strands to the core strand at a point on the modifiedly moving part of the core strand and at another point on the unmodifiedly moving portion of the core strand to be served thereon by the rotation thereof.

LEO L. WEAVER.
